UNITED STATES PATENT OFFICE.

HENRY GEORGE VOLCKENING, OF BROOKLYN, NEW YORK, ASSIGNOR TO CHARLES K. VOLCKENING, OF BROOKLYN, NEW YORK.

BOTTLE-WASHER BRUSH.

Application filed May 14, 1928. Serial No. 277,427.

My invention relates to bottle washer brushes, admitting of general use, but especially suitable for washing bottles of large size, such as milk bottles.

More particularly stated, my improved bottle washer brush is of the type known as a wire brush, made of wires twisted together to hold bristles therebetween, and so bent or formed as to enable the bristles to reach and effectively scrub the inside of the bottle to be washed.

My invention further comprehends a brush of simple construction and of such form as to enable it to be easily and cheaply made, and so that when damaged for any reason or when worn out, it may be readily discarded, or replaced by a new one.

Reference is made to the accompanying drawing forming a part of this specification, and in which like reference characters indicate like parts throughout the figures.

Figure 1 is a fragmentary elevation of my improved bottle washer brush and its mounting.

Figure 2 is a fragmentary side elevation of the same.

Figure 3 is a fragmentary plan of the brush and its mounting, certain parts being omitted or broken away.

A spindle 4 is made of metal and provided with a water passage 5 and with a nozzle 6, having the form of a tube, through which water is discharged from the central passage 5.

A pair of semi-cylindrical members 7, 7, serve as a brush holder for supporting the brush 8.

The brush is provided with separate portions 9, 10, 11. The portions 9 and 11 are supporting stems, and the portion 10, which carries bristles as shown, is located intermediate the portion 9 and 10, and is bent or formed into a loop, of ring-like form, which encircles the nozzle 6.

The portions 9 and 10 are each provided with a hook-end 14, the hook-ends being located in channels 13, for the purpose.

It will be noted that with the parts in position, as indicated in the drawing, the nozzle 6 extends upwardly past practically all portions of the brush, the portion 10 being bent around the nozzle, and spaced therefrom.

By this arrangement, the bristles of the brush extend upwardly a slight distance above the end of the nozzle, and the bristly

portion of the brush, as a whole, has a general rotund form, suitable for washing the entire inner surface of the bottle.

The portion 10 of the brush, formed into a loop as shown, enables the bristles to project not only upwardly but in practically all other directions in which they are required to project, in order to effectively reach all portions of the inner surface of the bottle to be washed.

During the operation of the machine, with my improved brush mounted in position as shown in the drawing and as above described, a bottle is mounted in a frame, the bottom of the bottle being uppermost. The spindle carrying the brush is next thrust upwardly through the neck of the bottle, to a limit at which the uppermost bristles of the brush are pressed against the bottom, and also against the concave inner surface bounding the bottom, of the bottle.

Then as the spindle is rotated and water is supplied through the central passage 5 and through the nozzle 6, this water is spouted hard against the bottom of the bottle, (now uppermost), which is at the same time brushed or scrubbed vigorously by the bristles.

It will be noted that the nozzle projects upwardly through and past the bristly portion of the brush, and discharges the water in close proximity to the bottom of the bottle; and that the bristles immediately adjacent the point where the water is directed as well as at points remote from this point of delivery, can easily reach the inner surface of the bottle.

The formation of the portion 6 into the proximate shape of a ring has more than one advantage. First, it so distributes the bristle portion of the brush that there are bristles on every side of the nozzle; and second, the ring-like form of this portion 10 enables the nozzle to be centered within it.

I do not limit myself to the precise mechanism shown as variations may be made therein, without departing from my invention, the scope of which is commensurate with my claims.

Having thus described my invention, what I claim as new and desire to secure by Letters Patent is as follows:

1. A device of the character described, comprising a spindle provided with a water passage, a brush mounting carried by said

spindle and provided with a nozzle for discharging water from said water passage, said brush mounting being further provided with channels, and a wire brush provided with stems extending into said channels for the purpose of supporting said brush upon said brush holder, a portion of said brush intermediate said first mentioned portions being formed into a loop of substantially circular form.

2. A device of the character described, comprising a spindle provided with a water passage, a brush mounting carried by said spindle and provided with a nozzle communicating with said water passage for the purpose of discharging water, and a brush carried by said brush mounting and provided with a portion formed into a loop encircling said nozzle.

3. A device of the character described, comprising a spindle provided with a water passage, a brush mounting carried by said spindle, a nozzle supported upon said brush

mounting and communicating with said water passage in order to discharge water therefrom, said nozzle having the form of a tube, and a wire brush connected with said brush mounting and carried thereby, said wire brush having a portion carrying bristles and bent to encircle said nozzle.

4. A device of the character described, comprising a spindle provided with a water passage, a nozzle carried by said spindle and communicating with said water passage, said nozzle extending from said spindle in order to discharge water, a brush holder carried by said spindle and disposed adjacent said nozzle, and a wire brush provided with a plurality of stems connected with said brush holder, said wire brush being further provided with a portion carrying bristles and bent around said nozzles.

Signed at Detroit, in the county of Wayne and State of Michigan, this 8th day of May, 1928.

HENRY GEORGE VOLCKENING.
